28 Claims. (Cl. 34—57)

This invention relates to a clothes dryer providing a new method for removing moisture from a quantity of wet garments and which provides an apparatus for carrying out the operative functions of the method employed.

Existing clothes dryers are almost all based on a rotating drum or cylinder principle, using cycle control means to vary the drying method according to desires or to various conditions of operation. But all dryers of this character are excessively and objectionably hard on garments specifically due to frictional wear. Some use wire basket drums, others use perforated drums and similar interrupted or apertured type surface designs for the drums or cylinders which all add to the frictional and abrasive wear, so to speak, of the garments that are subjected to the turning action of the revolving units in carrying out the drying action in devices of this kind.

Other objectionable features of known clothes dryers are the outgrowth of the numerous and complicated control mechanisms employed for cyclic manipulation of the dryers. Furthermore, excessively large heating elements are employed for lessening the drying time. These elements are expensive, power consuming and must be controlled carefully to prevent overheating and at the very best prove to be inefficient for the results actually obtained.

It must also be considered that all rotary drum and cylinder dryers need large substantial bearings and stout supports plus drives and belting or other means of speed reduction and control.

One of the objects of the present invention is to provide a simple, inexpensive light weight and comparatively small cabinet clothes dryer that operates on a different clothes drying principle and one that effectively removes water from garments over a very short time interval under efficient heat control operation.

Another object of this invention is to eliminate excess wear on garments with negligible lint removal or accumulation. Substantially all well known and popular clothes dryers must make lint disposal provisions, the excessive lint being due primarily to excess wear and abuse to the garments. No lint catching units or drawers are necessary with the dryer of this new construction and operation.

A further object of the invention is to provide an air jet principle to act upon the clothes with a unidirectional air flow, the air actually floating the clothes, so to speak, with the incorporation of a heating element of fixed capacity that is used, as is, throughout the drying cycle.

Another object of the method of drying clothes is to dispose a load of wash in a given air stream area and to force air through the load in one direction, taking in an air supply from the ambient air and again discharging it into the ambient air after passing through the clothes load. As a variation to this method, the air may be recirculated in part to again act upon the clothes and more than once.

A still further object of this invention is to provide a selective cyclic control to vary the drying action, as for example, over a range from damp dry to fully dry. In this respect, the control is a thermostatic switch arrangement that is temperature responsive to a given selected degree of clothes dryness or wetness as the case may be and wherein the control starts and stops the complete cycle as selected. The shut-off is automatic. This control

2

starts and stops the air jet mechanism and the heating element for the clothes drying air.

Another object of the invention is to provide a vertically arranged clothes receiving chamber with a tempered air source, blower and heating element at the bottom and an exhaust at the top, and to provide a thermostatic circuit control switch at a given height within or in a position of communication with said chamber and wherein the thermostat is directly thermally responsive to the temperature of the air attained in the cabinet at the thermostat location and preferably in a zone near and above the garment or clothes mass in the drying chamber.

The drying action on the wet clothes in the cabinet produces a situation wherein the cabinet walls and clothing remain relatively cool from the start of the drying cycle as air is forced into and through the clothes even with the addition of heat from the heating element. This is due to cooling by evaporation. Experiments have shown that this cooling phenomenon prevails during the portion of the cycle wherein the greater amounts of water are initially removed or extracted from the garments with the moisture removal tapering off during the cycle of operation. As the drying progresses, the lower portions of the walls of the chamber, and correspondingly the garments in the bottom of the chamber, become gradually warmer and hotter. As the water removal process continues, the clothes and the chamber walls become progressively warmer or heated upwardly in relation to the blower and heater location until all the clothes attain a given generally uniform temperature which is also evidenced by warmer chamber walls surrounding the vertical core of the clothes mass or batch. When the entire garment group becomes so heated or warmed the clothing has reached a given stage of dryness and as determined by the setting or selection of the thermostatic switch operation, the drying cycle circuit is automatically interrupted by this instrument which by its location in the exhaust air stream in the dryer then shuts off the blower and heater to conclude the water removal interval.

By setting the thermostat at selected shut-off temperatures, it is possible to retain a given minimum amount of moisture in the clothing or else to completely dry the batch all according to the operator's desires or as may be governed by subsequent clothes disposal or handling as to whether the clothes are to be ironed or are just to be put away in dry condition; or in conformance with any other condition of use having a direct bearing on a given moisture content in clothing or other articles submitted to the dryer.

As another object, the present invention contemplates the incorporation of a clock actuated timer in the control circuit of the clothes dryer to provide for a predetermined on and off period of operation. Under such a time control, the regulation of the drying function period may be accomplished within reasonably accurate limits. The blower creates a constant air supply and the heating element is made to function at full capacity transmission of energy so that no particular variance should normally prevail with these operational units. The only variance that may be encountered might prevail in the placement of the individual pieces of clothing and to some extent in the respective moisture absorption of these various garments. Another variable factor may be experienced by a marked change in the temperature of the ambient air that is drawn into the drying cabinet.

On the whole, the last two variables are normally of no great concern since the deviations will generally average out. Furthermore, with a strong constant capacity blower and a concerted constant heat input, the drying efficiency will be predicated primarily on these dominant and important factors which will readily overshadow the

comparatively small variations noted. Thus, a good timer will provide fairly consistent repeated results under appropriately selected cyclic periods.

Another object of the invention is to provide a simple method for drying articles in a tunnelled air stream and to provide means to control the behavior of such articles in said air stream to obtain a predominantly efficient drying action under such conditions of operation. This method is supplemented by the addition of a source of heat to induce better moisture absorption and dissipation.

Other objects and advantages inherently residing in the clothes dryer of the present design and invention and in the method of drying articles as herein set forth and defined shall hereinafter become apparent from the following detailed description having reference to the accompanying drawings forming a part of this specification.

In the drawings:

FIG. 1 is a vertical cross sectional view through the cabinet of a clothes dryer embodying the principles of the present invention therein, this section being taken in a transverse plane side to side of the machine and looking rearwardly from the forward interior portion of the machine and with the operating mechanisms there in generally shown in elevation;

FIG. 2 is a transverse plan sectional view through the clothes dryer as taken substantially along the plane of the line 2—2 in FIG. 1 and looking downwardly in the direction of the arrows;

FIG. 3 is another transverse plan sectional view taken through the clothes drying machine substantially along the plane of the line 3—3 in FIG. 1;

FIG. 4 is a further plan sectional view taken through the clothes drying machine along the plane of the line 4—4 in FIG. 1;

FIG. 5 is a fragmentary vertical cross sectional view taken through the lower portion of the machine and on an enlarged scale showing the operating mechanisms in section and as viewed substantially along the plane of the line 5—5 shown in FIG. 2;

FIG. 6 is a detailed vertical cross sectional view of the upper rear wall portion of the machine cabinet including the exhaust vent and the thermo-electric circuit switch mechanism all as viewed substantially along the plane of the line 6—6 in FIG. 1;

FIG. 7 is a sectional view analogous to FIG. 6, but showing a regulatory timing mechanism in the electrical operating circuit in place of the thermo-electric switch;

FIG. 8 is a diagrammatic circuit layout for the clothes dryer using the thermo-electric switch of FIG. 6 therein;

FIG. 9 is a vertical cross sectional view taken through the dryer cabinet and looking rearwardly thereof to diagrammatically illustrate the method of loading;

FIGS. 10 and 11 are transverse sectional views taken on lines 10—10 and 11—11 respectively in FIG. 9;

FIGS. 12 to 17 inclusive are views showing the manner of handling individual articles of clothing for the machine loading process;

FIG. 18 is a fragmentary vertical sectional view on the order of FIG. 9 illustrating the bottom portion of the machine in operation;

FIG. 19 is a fragmentary vertical sectional and detail view showing a modified arrangement of the clothes dryer mechanisms;

FIG. 20 is a plan view of the impeller unit per se as viewed along the line 20—20 in FIG. 19;

FIG. 21 is a fragmentary vertical sectional view as seen along the plane of the line 21—21 in FIG. 19;

FIG. 22 is a vertical cross sectional view taken along the line 22—22 in FIG. 23 illustrating another modified arrangement of the features of the clothes dryer;

FIG. 23 is a horizontal cross sectional view taken along the line 23—23 in FIG. 22;

FIG. 24 is a fragmentary sectional detail view of a swingable rack unit as seen along the line 24—24 in FIG. 22;

FIG. 25 is a plan view of the swingable rack per se;

FIG. 26 is still another vertical cross sectional view of a dryer illustrating certain other modifications in design of the dryer structure including a double walled cabinet;

FIG. 27 is a cross sectional view taken horizontally and in the plane of the line 27—27 in FIG. 26;

FIG. 28 is a fragmentary plan view of the FIG. 26 dryer;

FIG. 29 illustrates the lower portion of one other form of clothes dryer accommodating a high output heating coil and blower-motor arrangement as seen in vertical section;

FIG. 30 is a transverse horizontal cross sectional view taken along the plane of the line 30—30 in FIG. 29; and

FIG. 31 generally illustrates one commercial form of snap action set and thermostatic release electric switch that may be employed for circuit control in the dryers described.

Now, with more particular reference to FIGS. 1 to 8, the clothes dryer of the present invention consists of an upright machine providing a vertically arranged cabinet 1 mounted upon suitable casters 2, the cabinet 1 having an open bottom 3 and an open top 4 with a suitable lid or cover 5 hinged at 6 to one cabinet wall 7 to be swung from a vertically determined clothes loading position substantially as shown in broken lines in FIG. 6 to a cabinet closing position as best illustrated in full lines in FIGS. 1 and 6.

Wall 7 is here considered as the rear wall of cabinet 1, with walls 8 and 9 providing the opposite side walls thereof and wall 10 providing the front wall of the machine. As best seen in FIGS. 2, 3 and 4, the cabinet is generally rectangular in cross section and the straight walls 7 to 10 are adjacently joined by the respective vertical curved corner sections 11, 12, 13 and 14 to prevent sharp cabinet corner cavities or formations and at the same time providing a large capacity clothes carrying cabinet for the purposes herein described.

The operative clothes drying or moisture removing mechanisms of the machine are assembled and situated at the bottom of the cabinet and preferably just upwardly of or inwardly of the cabinet open bottom 3. The main operating units of this bottom mechanism assembly 15 consist of a motor 16, an air impeller or fan 17 and a heating apparatus 18. The divisional cavity arrangement providing a continuous air flow path into and upwardly within the cabinet 1 primarily consists of an annular air inlet chamber 19 receiving ambient air through the opening 3 of the cabinet bottom, a filtered air inlet chamber 20 surrounding and including most of the motor 16 and an upwardly opening annular trough air exhaust chamber 21 that partially houses and surrounds the impeller 17 and also the upper portion of the motor 16.

This entire assembly 15 is carried upon the cabinet as a composite unit by a simple and unique combination of baffle and division wall structures that together form the connected and contiguous air chambers that guide and direct the air flow in a path into the cabinet under the direct creation and control of the revolving impeller 17 when actuated by the motor 16, the air tunnelling through the entire area of the cabinet.

The construction of the assembly 15 includes a base plate 22 welded or otherwise secured to the upper side 65 of a strut or cross brace 23 which is in the form of an inverted channel made with flattened ends 24 and 25 which seat upon the inturned cabinet portions 26 and 27 respectively of the cabinet terminal flange 28 that encircles and outlines the cabinet opening 3. Suitable 70 nut and bolt fastening units 29 secure the strut ends to opposite portions of the cabinet flange 28.

A plurality of resilient mountings 30 including the motor assembly bolts 31, spacing nuts 32, spaced rubber bushings 33 and 34, and securing nuts 35 are employed 75 to attach the motor 16 to the base plate 22. The bolts 31

pass through suitable clearance apertures provided in plate 22 so that no supported metal directly touches the plate 22 while the rubber bushings act as the main supporting reactionary feet for the motor 16 and to counteract noise and vibration transmittal to the cabinet structure proper.

The resilient motor mountings 30 include a plurality of brackets 36 that support an annular ring 37 to which the heater mountings 38 are secured. Mountings 38 include the insulating bushings 39 that carry the resistance coil 40 of the heating apparatus 18. This described heating coil supporting arrangement disposes the resistance coil 40 annularly about the motor and spaced therefrom, while placing the coil in the air exit or exhaust part of the filtered air inlet chamber 19 and just beneath the impeller or fan 17.

Assembly 15 further provides an annular diaphragm or shroud 41 arranged in vertically spaced relation with respect to the base plate 22. It should be observed that the base plate 22 horizontally occupies the central cabinet area and that the shroud 41 covers or occupies the balance of the horizontal cross sectional area of the cabinet, although both such baffle units are vertically spaced to provide an annular air inlet communication space between the respective air inlet chambers 19 and 20.

The shroud is vertically supported from the base plate 22 by means of a plurality of legs 42 having radially inwardly formed feet 43 welded or otherwise secured to plate 22 and also having radially outwardly formed feet 44 that are welded or otherwise suitably fastened to the bottom of the shroud 41. Shroud 41 is made with a central air intake opening 45 provided in the flat bottom 46 thereon which is contiguous with the upsweep or up-curved peripheral impeller encircling rim 47 that terminates in an upper horizontal shelf or ledge 48 shaped to fit the cabinet interior area as outlined by the cabinet walls. Thus, with base plate 22 rigidly secured and supported upon the bottom cabinet flange 23 by means of the supporting channel strut 23 and by the provision of the supporting and connecting legs 42 carrying the shroud which neatly fits the cabinet, this entire assembly plus the motor and fan or impeller are all oriented and supported in well stabilized relation within the cabinet and adjacent the bottom air entry opening 3 in the cabinet 1.

A suitable replaceable air filter 49 of circular form and of a height to reach from the shroud 41 to the base plate 22 is assembled about the plurality of legs 36 and functions to remove dust and airborne foreign matter from the air that is drawn into the cabinet and directed against and through garments or articles of clothing that are in the tunnel area of the cabinet for moisture removal.

The fan or blower impeller 17 of the assembly 15 is carried in horizontal relation partially nested within the annular shroud 41 by means of a hub 50 that is pin connected at 51 with the vertically extended shaft 52 of motor 16. Impeller 17 is a composite sheet metal assembly of an upper disc or web 53 to which are welded or attached a plurality of arcuate vanes 54 that are well shown in FIG. 3. Each vane 54 is a channel piece providing an air impelling vane wall 55 terminating with upper and lower vane attaching flanges 56 and 57 as shown in FIGS. 3 and 5. The impeller vanes 54 are propelled in a clockwise direction by the motor as viewed in FIG. 3, with the larger body portions of the vanes operating in a path disposed radially outwardly of the opening 45 and in the annular shroud 41 with the radially inner ends of the vanes operating in vertical alignment with the outer annular portion of chamber 20 but thereabove.

The impeller is the operating instrumentality that draws in ambient air through the cabinet bottom 3 into chamber 19, through the filter 49 into chamber 20 where heat is absorbed from both the heating apparatus 18 and from the motor 16 and then through opening 45 into the im-

peller shroud 41 for both radial and upward discharge in large volume quantities under the high speed rotation of the motor. A motor speed of approximately 3000 r.p.m. has been found quite satisfactory under average operating conditions.

The top or uppermost member of the assembly 15 is an apertured clothes or garment supporting unit 58 that is best illustrated in FIGS. 1, 2 and 5. This supporting unit 58 comprises a dome shaped screen 59 having a central inwardly dished screen section 60. The lower part of the dome portion 59 of the supporting unit 58 is surrounded by a shelf or horizontal table section 61 that conforms with the contour of the cabinet as best seen in FIG. 2. The shelf section 61 of the screen terminates with a vertically arranged peripheral supporting flange 62 to space the shelf or table section 61 in a given relation above the shelf or ledge 48 of the shroud.

To reinforce the screen unit 58 and for the support of

heavy wet clothing or garments, a band 63 having a lapped edge 64 is supported on a plurality of channel iron stock legs 65 that are welded or otherwise secured to the outer face of the band 63 and radiate therefrom as best shown in FIGS. 2 and 3 into positions to bisect the curved corner portions of the cabinet 1. Each leg 65 has a foot 66 that rests upon the shelf 48 of the shroud 41 and an arcuate upright 67 that follows the contour of the screen crown 59 to meet the band 63. As will be observed, band 63 lies coincident with the circular junction 68 of the crown 59 and the contiguous adjacent periphery of the dished section 60, keeping the support at this point of the screen, which is the highest portion of unit 58.

A clothes control arrangement in the form of a rack 69 is adjustably supported intermediate the vertical height of the cabinet. This arrangement functions as a garment stabilizing means with more particular reference to its action in cooperation with smaller clothes loads per se or to function in the same capacity for greater clothes loads that are placed or positioned within the cabinet

both below and/or above the rack location. The rack provides a maximum rise position for the clothing or garments that are placed and carried upon the apertured unit or screen 58. Not only does the rack determine the maximum rise limit of the cabinet clothing core, but the rack counteracts clothing disarrangement and tilt so that the blower air supply as created by the impeller will, for the greater part, pass into and through the garments for optimum drying efficiency. Greater moisture absorption results in direct blower air clothes penetration. By keeping the garments in piston fashion in cabinet chocking positions and holding them so arranged, the drying cycle is held to a minimum and better results are obtained through a substantial automatic fluffing of the garments from good and complete air penetration.

Rack 69 is made from rod or bar stock formed into a rectangular frame having a front bar 70, side bars 71 and 72 and aligned rear bar ends 73 and 74 which terminate in vertically arranged parallel guide bars 75 and 76. A short length of bar 77 is connected with one of the bar ends 73 or 74 and extends across the central gap at the rear of the frame that lies intermediate the guide bars 75 and 76. By having the aligned rear bar ends free to move relatively to each other, spring in the frame will act upon the guide bars 75 and 76 to frictionally act upon the bar receiving frame mounting means 78 to hold the rack in a vertically adjusted position.

The mounting means 78 is constructed as a bracket 79 secured to the cabinet wall 7 by welding, etc., and this bracket provides spaced side wings 80 and 81 which each terminate in reentrant loops 82 and 83 to form vertical sleeve guide members to slidably receive the guide rod portions of the frame that were above described as the guide bars 75 and 76. Preferably pins 84 and 85 or other stop means are connected with the upper ends of the

guide bars to prevent complete withdrawal of the rack 69 in a downward direction.

As seen in FIG. 2, the rack 69 is made in the form of the rectangular open centered frame and is spaced inwardly and away from the cabinet walls but generally following the surface contour thereof. Additionally, cross rods or links 86 and 87 are provided with eyelet ends 88 and 89 respectively, which eyelet ends are slidably mounted on the frame side bars 71 and 72. When the rack is in its operative position to coat with the clothes, the cross rods are normally located in the positions shown in FIG. 2. When loading or unloading the machine, the cross rods may be moved toward the ends of the rack, either to the front or rear thereof, or both to the front or both to the rear, leaving a clear open centered rack for loading purposes.

The cabinet may further include a shelf such as 90 in FIG. 6 on one or more sides thereof or which can be made to encircle the entire open end 4 of the cabinet to provide, in either case, another clothes rise limiting means at a higher elevation than the rack to prevent excessive upward movement or disarrangement of the garments under the action of the updraft air current that acts upon the clothes load in the cabinet. Normally, this upper shelf structure is not too critical, but it may be here mentioned that more than one rack such as 79 may also be employed in different elevations in the cabinet if desired. Then also, these racks do not compress or seat upon the clothes carried thereunder. They allow a certain amount of freedom of action of the respective garments of the load within the cabinet with a limited amount of shifting of the garments in each layer which has been found advantageous in obtaining efficient and controlled drying results. However, as explained previously, the racks do keep the garments generally in wall to wall relation and in cabinet choking positions as previously pointed out.

It should also be apparent that the shape of the apertured unit or screen 58 further contributes to the best clothes arrangement by keeping the various pieces of clothing in positions to accept and permit air penetration for the drying function to be carried to a quick and efficient conclusion.

Referring now to FIG. 6, the cabinet is provided with one or more exhaust openings or ports 91 located immediately below the lid or cover 5. A suitable shield 92 protects the openings 91 from becoming covered by small articles such as handkerchiefs or clothing parts. This shield is secured to the cabinet and is formed as shown with open sides for air flow out of the cabinet and ports. It has been found that under certain conditions of operation that the lid or cover 5 may also lift under air pressure to let some of the moisture laden air out of the cabinet top opening 4.

The power supply and circuit control mechanisms may best be described with reference to FIGS. 1, 5, 6 and 8. A power service cord 93 with a conventional plug 94 may be connected with the usual house line circuit through a wall socket or the like to bring the supply current through wire 95 to a thermo-electric switch 96 that is confined within a moisture sealed housing 97. Switch 96 includes a suitable thermal responsive make and/or break contact 98 which may be regulated to operate and open the circuit at different selected temperatures as by means of an adjustment knob 99. Any conventional thermo-electric switch of this character will function when used in the described location as best illustrated in FIGS. 1 and 6. In general, the switch is of the push button set snap action type that closes the circuit with one of the contacts being bimetallic and heat responsive to break the circuit when subjected to a given temperature.

Through switch 96, the supply current is conducted by wire 100 into and through a conduit 101 that leads out of an opening 102 in cabinet wall 7 and through a protective housing 103 attached to the cabinet wall 7.

Conduit 101 reenters the cabinet through an opening 104 and leads to a grommet arrangement 105 in base plate 22 and into the filtered air inlet chamber 20. Wire 100 is then branched or divided with one lead 106 going to motor 16 and the other lead 107 going to one end of the resistance coil 40 as best shown in FIGS. 3 and 5.

Return circuit wires or leads 108 and 109 come from the motor 16 and from the other end of the coil 40 (see FIG. 3) and join the wire 110 that reenters the conduit 101 and leads back upwardly to the power cord 93 as best shown in FIG. 6. The same general arrangement is also well illustrated more diagrammatically in FIG. 8.

It has been discovered and determined that the drying operation of a batch or load of clothes follows a predetermined pattern of both moisture and heat dissipation. At the start of the drying cycle, the entire cabinet remains fairly cool and as the cycle progresses, the cabinet warms up from the bottom with the warmth travelling upwardly as the clothes begin to lose their excess water.

20 This indicates that the moisture removal brings about a cooling by evaporation even with the introduction of heat into the air stream.

This action further revealed the fact that when the entire clothes load become warm that a substantial predetermined dryness had been attained, as for example, a damp dry stage. By continuing the drying cycle the clothes could be entirely dried as they become still warmer.

25 By taking advantage of this particular phenomenon and locating the thermo-electric switch 96 as described in a region above the normal top level of the clothes load, this switch after it is button actuated to "On" position, will be in a heat responsive state to shut off when a predetermined temperature is attained in the zone surrounding the switch location. By using an adjustable means to vary the actuation of the bimetallic switch contact so as to operate at a given selected temperature, the degree of clothes dryness can also be regulated thereby to suit the desires of the operator.

30 To make the thermo-electric switch more sensitive to the attainment of a given temperature, the housing 103 on the back wall of the cabinet is made considerably larger than necessary to carry the conduit 101 so as to function in the capacity of an air conductor or flue acting as a chimney whereby to bring cabinet warmed air from the lower portion of the cabinet into the housing 97 and to the bimetallic switch part for preheating purposes. This cuts down the lag in the final interval of heat transmission to the housing 97 and to the switch operating 35 parts making the switch react quicker to the cabinet clothes load temperatures.

35 The warm air circulation into the thermo-electric switch housing 97 is preferably kept in motion by suitably located bleed openings 111 formed in the cabinet wall 7 in a position to be covered by the housing 97. An adjustable apertured slide plate 112 can also be employed in cooperation with the bleed openings to provide a regulatory means for suitable variation of the amount of air that may be bled out of the tube or conduit 103 and out 40 of the housing 97.

45 Referring to FIG. 7, this illustrates the use of a timer in place of the thermo-electric switch arrangement just described. It is understandable that certain clothes loads will dry in this machine to a reasonably determinable amount of dryness over a given period of machine operation. Repetition of like loads for like periods, should therefore, give fairly consistent results. For this reason, a clock timer 113 of a conventional type with a time regulating knob 114 may be placed into the same machine 50 circuit for selecting predetermined time cycles for drying operation. The present machine has constant blower air flow and constant heat introduction and is, therefore, well suited for a clock timer cycle control.

55 Some variation in operation may occur in the machine loading of the machine by the operator, but with a little

care, this loading will and should be fairly uniform for each drying function to thereby obtain fairly consistent results each time the machine is used and the time cycle adjusted according to the selected setting of the timer.

The method of loading and operating the clothes drying machine may best be understood with reference to FIGS. 9 to 18. In FIGS. 9, 10 and 11, the preferred procedure is best depicted. The lower or first wet garments 113 are placed in the bottom of the cabinet and in parallel rows all in one general direction over screen 58 as shown in FIGS. 9 and 10, the garments being made to well fill the cabinet from wall to wall thereof.

The next layer or added wet garment 114 are then similarly placed over and upon garments 113 in a like manner, but in generally parallel rows angularly arranged to the rows of garments 113. In the drawings the rows of garments 114 are placed at right angles to the rows of garments 113.

Rack 69 is then adjusted to position shown in FIG. 9 leaving a predetermined clearance 115 between the upper garments and the rack. Cross rods 86 and 87 of the rack are then adjusted into positions as shown in FIG. 2 from their positions to the ends of the rack to initially permit clothes loading through the rack and upon the screen, etc. With such clearance as 115, the garments will have the opportunity to float upwardly as they dry and upon the upwardly directed air stream under the pressure of the air delivered from or created by the impeller 17 in the cabinet through the screen 58 and against and through the fabric of the garments.

A number of additional layers of wet garments 116, 117, 118 and 119 are then placed in successive rows upon and over the rack 69 and in crisscross fashion to bring the load up to the usual capacity for the machine which may vary in amounts up to approximately eight pounds. The clothes load in and of itself acts as a piston in the cabinet which is first moisture laden and which begins to float as the drying progresses.

In actual dimensions, this dryer cabinet measures about 16" x 16" and stands about 30" high. The bottom carries the mechanisms described plus the screen top and the load is at its maximum when at the general level shown in FIG. 9. From this it is evident that a large clothes load is dried in a relatively small unit in comparison to the much larger more popular clothes dryers that are on the market. It is also again to be emphasized that the dryer herein disclosed and described does not subject the garments to the usual rotary and tumbling action as in revolving cylinders and the like that form the usual clothes carrying mechanism of such popular dryers.

With the clothes arranged in the dryer as described, the control switch 96 is then turned on to start the motor, fan and heater to set off the drying cycle of operation. The motor and fan immediately come to speed and operate in the dryer at their full speed while the heater coil also receives its full capacity current to give off its maximum heat radiation which in this machine is rated at 1000 watts capacity. The motor speed is preferably 3000 r.p.m. with the use of the 13 $\frac{1}{16}$ " outside diameter fan unit.

As the air is forced upwardly into and through the garments the maximum amount of the moisture per unit of time is removed in the first period of the total cycle. The moisture removal then tapers off, but as an average, approximately 1 oz. of water is dissipated per minute. The garments are floated on air during the process with the lower portion of the load being held at maximum rise by the rack 69. As the drying progresses, the cabinet begins to warm as the clothes heat up. This continues until the entire load has come to a given selected temperature which, as previously explained, causes actuation of the thermo-electric switch 96 by the heated exhausted air to automatically open the circuit shutting off the dryer mechanisms. It has been determined that at 100° F. at the switch level that the garments are quite dry. The

maximum operating temperature ranges at about 130° F. plus or minus 10° F. by selecting lower temperature responsive shutoff points on the switch dial, varying states of garment dryness are obtained according to the desires of the operator.

One other factor has been determined in connection with the vertical cabinet temperatures. In the height of the cabinet it has been found that only an overall variation of 5° F. exists. Thus, if the lower portion of the cabinet is found to be 100° F. the upper part of the cabinet will range at 95° F. Should the upper portion of the cabinet check at 115° F., then the lower portion of the cabinet can be assumed to range at 120° F., etc. This indicates the consistency of the heat dissipation and how it progresses during evaporation in the cabinet from the input at the bottom plus its uniform pattern progressing upwardly through the garments.

The garments are slower to respond to the heat at the beginning of the cycle due to the maximum water content. Also the excessive amount of the initial moisture evaporation actually causes a cooling in the cabinet and contents which develops into warming and eventual heating as the moisture is proportionally removed by the heated air blast through the air pressure potential. This whole composite action lends itself to the heat responsive control means and to the selective final moisture retention or removal situation depending upon the manner in which this final drying procedure is analyzed.

Tests have revealed the efficiency and effectiveness of the dryer. In referring to clothes weights, 4 lbs. of clothes are actually 8 lbs. of wet garments so that the total weight is generally double the dry garment weight. A 4 lb. load has been thoroughly dried in 45 minutes to 1 hour. A load of 6 lbs. has been dried in 1 hour to 1 $\frac{1}{2}$ hours. And a 9 lb. load has been dried in 2 $\frac{1}{2}$ hours operation of the particular dryer described.

In explaining the operation of the dryer and the criss-cross arrangement of the clothing or individual garment pieces, FIGS. 12 to 17 illustrate the general manner in which the various garments can be handled to loosely arrange the directional layers and to obtain the most effective loading of the machine. A generally flat piece 120 in FIG. 12 may be grasped at 121 by one hand and then grasped below in either direction as shown by arrows 122 and 123 to collect the clothing piece in an elongated loosely folded or gathered arrangement as at 124 in FIG. 14. In this way the article can then be easily placed into the cabinet accordingly as shown in FIGS. 10 and 11, etc.

Similarly, a shirt 125 may be taken hold of with one hand by the collar 126 as in FIG. 13 and then laterally grasped by the other hand as shown by the arrows 127 and 128 to be loosely gathered into an elongated arrangement as at 129 in FIG. 15 for placement or arrangement in the cabinet.

In some instances, certain pieces of wash 130 may be held as in FIGS. 16 and 17 and more or less dropped or lowered into suitable superimposed loose folds 131 upon the cabinet screen diagrammatically shown at 132. The same crisscross idea can thus be followed with subsequent articles of wash.

In general, the main object is to fill the cabinet from wall to wall. The garments need not be too orderly placed, but can be overlapped somewhat in the machine loading process. Primarily, twisted and packed wet pieces should be shaken and loosened to prevent packing and plugging so to speak of an air zone or channel area before they are dropped into the cabinet. The layer and crisscross arrangement of the articles of clothing provides a good air block system to carry out the drying of the clothing in the clothes dryer described with a high degree of efficiency.

FIG. 18 diagrammatically shows the machine in operation during the clothes floating stage with the lower load of clothes 133 lifted above the screen and in stabilizing contact with the underside of the rack frame 69. The upper clothes load 134 may be floating as shown above

the rack. The rack also provides an efficient apparatus for use when drying small clothes loads which are more prone to disarrangement under blower pressure conditions.

The foregoing description has been directed to a preferred clothes dryer constructed according to the fundamental concept of the present invention and to thereby show one means whereby to carry out the method of drying clothing according to the general principles herein set forth. Referring now to FIGS. 19, 20 and 21, a modified construction is there shown to illustrate certain changes in the details and arrangement of construction of the lower portion of the dryer but with the balance of the design generally following the first described form.

In FIG. 19, a shroud 135 is utilized and so formed as to provide restricted throat or opening 136 that is outlined or defined by the upstanding annular flange 137 that flanks a part of the lower portion of the inner peripheries of the fan blades 138. With this arrangement any reverse flow of air moving as per arrow 139 due to the pressure potential of the exhausted air at 140 will be upwardly directed at the flange 137 to again join or become a part of the inlet fan air so as to be redirected radially outwardly and upwardly by the blades 138 of the fan structure 141.

The power supply cable 142 in this construction is shown as passing through the annular air filter 143. Filter 143 is carried upon the base plate 144 and behind a retaining flange 145 and is in the form of a wrap around member having its edges 146 and 147 coming together along the parting line 148.

The shroud 135 and base plate 144 are joined by spaced brackets 149 welded or otherwise secured to the members connected thereby. The bracket 149 shown in FIG. 19 is coincident with the parting line 148 of the filter 143, and an opening 150 in bracket 149 is provided with a grommet 151 for the reception of the cable 142. The cable passes between the ends 146 and 147 of the filter 143 and a retaining ring or clip 152 holds the cable end 153 in supported position in relation to bracket 149 as shown in FIGS. 19 and 21 with the cable wires 154 and 155 being appropriately connected with the motor 16 and heating coil 40 as in the first described form of the invention.

Another modified construction of clothes dryer 156 appears in FIGS. 22 to 25. Here a horizontal screen 157 covers the dryer mechanisms 158 and supports a honeycomb air channelling and directing unit 159 having two sections 160 and 161 with walls generally vertically disposed in edgewise position to the airflow. A vertically arranged baffle or upstanding support in the form of a corrugated panel 162 is sandwiched between sections 160-161 and supported upon screen 157 as best shown in FIG. 23.

In this particular clothes dryer, the mechanisms 158 include an involute blower 158a having a filter or screen 158b covering the inlet opening 158c, with the blower outlet 158d exhausting into the dryer cabinet through an opening 158e in a transverse cabinet baffle 158f. A motor 158g is connected to drive the blower shaft 158h, either directly or through other suitable drive means. In addition, heating coils 158k are suitably mounted in the inlet air stream for tempering the blower air. The power supply to the motor and coils may be arranged as in the dryer construction shown in FIGS. 1 to 8 and controlled through the same or similar equipment as therein disclosed.

The dryer 156 also shows a swingable clothes stabilizing rack 163 supported upon a hinge 164 that can be vertically adjusted along suitable guiding clips 165 and 166 to be locked in place by a set screw 167. A rubber roller 168 depresses into a detent depression 169 in wall 170 of the cabinet to hold the rack in fixed position in the one position shown in FIG. 24. Other detents like 169 may be used or else the rack may be entirely frictionally held by compression of the roller per se against

the cabinet wall. The swingable rack 163 or rack 69 for that matter may be made narrower in width to support garments in draped relation thereover if desired while still functioning as means to prevent excess clothes

5 lift by the air.

The cabinet in this form shows air exhaust openings 171 located at the top and a depending apron 172 surrounds the clothes loading opening 173 that is formed with a clothes stopping edge 173a to prevent upward 10 movement of garments at that level. Apron 172 also shields openings 171 by reason of its location as shown in FIG. 22, the apron being outwardly positioned from the walls of the cabinet having such openings therein. One other change is apparent in that the electric thermo- 15 switch unit 174 is here carried in the shelf 175 and at the top table portion of the cabinet as best seen in FIG. 23.

The rack 163 of the present form has fixed cross rods 176 as best illustrated in FIG. 5. By the swingable nature 20 of the rack, loading need not be done through such rack. The rack can readily be swung into the upright position as shown in broken lines at 177 in FIG. 24 for loading the cabinet beneath the rack location as will be apparent from the design thereof.

25 FIG. 26 illustrates a dryer 178 using a cellular cross-cross air directing honeycomb 179 having individual cells 180 defined by angularly disposed walls 181 and 182. A circular clothes festooning upright baffle wall 183 is here employed in place of the festooning corrugated wall 30 162 in the FIG. 22 construction. The garments can be supported as shown in broken lines in FIG. 26.

This cabinet 184 of the dryer 178 has an inner chamber 185 and an outer cover or shell 186 to form an air space 187 therebetween. The air that is forced upwardly 35 through the clothing and cabinet is exhausted upwardly through the cabinet loading opening 188, then downwardly through the cabinet table top openings 188a in FIG. 28 to partially exhaust to atmosphere through outlet port openings 188b located in the outer shell 186 at the upper end of the cabinet. However, a certain amount of the air is redirected through the double walled portions 40 of the cabinet to again reenter the air inlet structure through cabinet openings 189. Cover or lid 190 is located over the cabinet top to provide the air deflecting 45 member for the cabinet opening 188 and ports 188a in the cabinet top surface.

In the previously described forms of the invention, a 110 volt circuit was normally intended to supply energy to the motor 16 and to the heating apparatus 18. Under 50 certain other conditions of operation and in localities where it is customary to provide 220 volt circuits, a clothes dryer of the design shown in FIGS. 29 and 30 has been devised with certain changes being evident in the power, heater and blower mechanisms and the arrangement there- 55 of to produce a more efficient unit. The balance of the clothes dryer in FIGS. 29 and 30 conforms with the design shown in FIGS. 1 to 5 using the same coating clothes sustaining and orientation means and devices.

As shown in FIG. 29, the motor 191 is supported by 60 the channel 192 and base plate 193 in the air intake chamber 194 defined by the base plate 193, air filter 195 and the annular baffle 196 which includes the exhaust throat or air opening 197 leading to the blower or fan chamber 198 of the fan or impeller 199 carrying the air propelling 65 vanes 200. The heating apparatus 201 having a coil 202 is supported by the bracket means 203 mounted upon the motor 191 and arranged to position the heating apparatus 201 above the motor as well as radially away therefrom. The fan 199 incorporates auxiliary blades 204 within the 70 coil 202 for the purpose of driving the air outwardly across the heating coil and to better dissipate the radiant heat to keep the motor 191 cooler to safeguard against overheating and to guard against poor and inefficient operation of the motor per se.

75 Additional cooling fan means 205 can be incorporated

into the motor assembly to also aid in carrying off excessive heat.

The fan chamber 198 is defined by the diaphragm or baffle 196 and the clothes supporting screen or perforated member 206. A cross brace 207 with legs 208 stands upon the baffle 196 and supports the overlying screen 206. An annular rim 208' is secured to the legs of the cross brace and the edges 209 of the screen 206 are turned under the rim to secure the screen in place over the cross brace.

By reason of the greater capacity heating unit output, which may average 3000 watts if so desired, the walls of the cabinet surrounding the discharge area of fan 200 may become too hot for safety. To shield this wall area or zone, a lining of asbestos 210 may be interposed between baffle 196 and the screen rim 208' as best shown in FIG. 29.

Thus, with the efficient and novel arrangement of the operating units as shown in FIGS. 29 and 30, cool inlet air is drawn into the bottom of the cabinet for entrance into the air filter and into the motor chamber to pass over and around the motor and as further aided by the small motor fan 205, the air then entering chamber 198 through the opening 197 to be directed across the heating apparatus 201 for radial and upward dissipation into the clothes chamber by the blower fan 199 aided by the auxiliary use of the blades 204 as described for directing excessive heat away from the motor 191.

Obviously, the latter dryer construction in FIGS. 29 and 30 can be regulated and controlled as in the other forms of the invention as by a thermo-electric switch or by means of a timer if so desired.

While the thermo-electric switch means 96 of FIGS. 6 and 8 has been diagrammatically illustrated, attention is directed to one commercial form of such a switch which is best illustrated in FIG. 31. Briefly, two contacts 211 and 212 are provided for the wires 95 and 100 shown in FIG. 6. The contact 212 connects with a composite blade 213 carrying the contact 214, this structure being in the nature of an over center snap unit that will move into the position shown under a given temperature condition. A second switch blade 215 with contact 216 coacts with a backup unit 217, blade 215 being connected with contact 211.

The regulatory mechanism 218 and switch closing means is mounted upon the switch plate 219 and comprises a push knob 220 with an attached stud 221 and a pressure or biasing stud 223. A spring 224 holds the stud 221 out. Pressure upon the knob 220 sets the switch contacts 214 and 216 into operative contact and they hold this position due to an over center snap action of the composite blade 213. Under a given temperature the blade unit 213 opens the contacts to open the circuit.

A pair of gears 225 and 226 provide means for threading the biasing stud into or out of the threaded socket 227 to urge point 228 of the stud 223 into greater or lesser pressure contact with the composite blade 213 to either retard the temperature release thereof or to accelerate this action thereby providing a regulation for the operation of the switch into open position under certain given temperatures.

The gear 225 is a wide faced gear to permit the knob 220 to set the switch as described while at the same time the gears will remain in meshed engagement to always provide operative rotative action for setting the cut off cycle of the switch.

With a switch of this character, the drying cycle of any one of the machines described can be determined by the operator. The switch may first be set to a given temperature for release and then push button closed by pressure upon the knob 220 to start the dryer. After the selected temperature is reached in the zone over and above the clothes load, the switch will automatically open to cut the current supply, stopping the motor and heater simultaneously.

Although the above disclosure has been directed to certain specific designs of clothes dryer, it is obvious that changes may be made to some degree without departing from the fundamental concept of the invention.

5 Any modifications of the individual elements or in the combinations thereof shall, however, be governed by the breadth and scope of the appended claims directed to the device of this invention.

What I claim is:

- 10 1. A clothes dryer comprising an upright chamber having vertically arranged walls defining both the chamber and an opening across the lower portion thereof, means within said chamber operative to direct air through said opening and into the complete cross sectional area 15 of said chamber, supporting means in said chamber to sustain articles of clothing in stacked relation across the full maximum area within the chamber and directly in the path of the air stream flowing through said chamber, and limit means provided intermediate the height 20 of the chamber to prevent certain of the articles of clothing from being radically displaced or upwardly actuated beyond a predetermined level above said supporting means by said forced air stream, said limit means comprising a vertically adjustable openwork rack unit 25 traversing the chamber in a given elevation spaced above said article supporting means to prevent the articles of clothing located therebeneath from rising higher than the selected location of said unit, said rack unit providing a second supporting means to carry additional articles of clothing thereon in tandem relation to the other articles of clothing and in said same stream of forced air.
2. In a clothes dryer of the character set forth and defined in claim 1, but wherein said rack unit consists of an open loop frame generally following the inner contour of said chamber but spaced therefrom, and cross wires shiftably mounted on spaced portions of said loop frame, said wires being adapted to traverse said chamber in positions across said loop frame and being shiftable to side portions of said loop frame to provide an open center for loading articles of clothing therethrough into the lower portion of said chamber.
3. A clothes dryer comprising a container having an opening therein, cooperative blower and heating units arranged to force tempered air through said opening into 45 said container, and means to retain articles of clothing within said container and directly in said stream of tempered air, said blower unit providing an air stream with sufficient force to penetrate through the articles of clothing positioned by said retaining means within said container, said retaining means including a perforate 50 crown member having a downwardly and outwardly sloping peripheral portion in said chamber and having a downwardly dished central portion contiguously arranged within said peripheral portion.
- 55 4. In a clothes dryer as in claim 3, but wherein said crown member is disposed adjacent to and in close proximity to said chamber opening and directly in the path of the forced air stream entering said chamber.
5. A clothes dryer comprising a clothes receiving cabinet having an open bottom, a lid to close the top, and a clothes drying unit including clothes supporting means all carried in the open bottom of said cabinet, said unit comprising a motor and connected air impeller, a shroud to confine said impeller having perimeter contact with the walls of the cabinet and being provided with an opening at the area surrounding the motor, a base plate arranged adjacent said motor and spaced from said shroud to coact with said shroud to provide an air intake space surrounding said motor and communicating with said impeller, and said supporting means comprising an openwork floor structure carried upon said shroud and spanning the air stream area to receive the air blast from said impeller and to support clothing in said air stream.
6. In a clothes dryer of the character set forth and defined in claim 5, but wherein said motor and impeller are 70

mounted upon said base plate, and said shroud and base plate are connected by brackets having projecting legs, said cabinet having inturned flange means at the open bottom of the cabinet, and said bracket legs being constructed and arranged to seat upon the cabinet flange means to support the entire clothes drying unit and its associated clothes supporting means upon said cabinet flange means.

7. In a clothes dryer of the character set forth and defined in claim 5, but wherein air filter means is disposed in said air intake space and supported between said shroud and the coacting base plate to restrain the infiltration of dirt and other foreign matter into the air stream and into the clothes drying zone.

8. In a clothes dryer of the character set forth and defined in claim 5, but wherein said openwork floor structure comprises, in combination, a screen resting upon said shroud, a cellular unit carried upon said screen, and a division wall projecting upwardly from said cellular unit to provide elevated means wherfrom to festoon clothing over and upon the screen and cellular unit.

9. A clothes dryer comprising a clothes chamber, perforate division means traversing said chamber, air propelling mechanism constructed and arranged to force air through said division means into said clothes chamber, a multiple wall member supported in edgewise relation with respect to said division means to provide a plurality of vertical cells to direct the propelled air in divided multiple jets into and through the clothes in the chamber, and an upstanding wall unit associated with said multiple wall member, said wall unit, the multiple wall member and said perforate division means all comprising coacting clothes supporting means to carry portions of the articles of clothing at variable elevations and in forced air receiving relation over and adjacent the air supply source.

10. In a clothes dryer of the character set forth and defined in claim 9, but wherein a rack member is swingably supported at one side of the chamber and adapted for actuation from a raised position adjacent one chamber wall to a lowered position across the chamber and into a predetermined spaced elevation above the coacting clothes supporting means.

11. In a clothes dryer of the character set forth and defined in claim 10, but wherein said rack member is formed to follow the peripheral contour of the chamber walls but spaced inwardly therefrom when said rack member is disposed in lowered position, said rack member including releasable orientation means arranged for coaction with a chamber wall to hold said member in its cross cabinet position and in a given relation with respect to the clothes supporting means.

12. In a clothes dryer of the character set forth and defined in claim 9, but wherein said upstanding wall unit comprises a corrugated division wall set on edge and extending across the chamber, with the convolutions thereof at the opposite outward sides of the wall.

13. In a clothes dryer, a clothes receiving cabinet to provide a clothes confining chamber, and a clothes drying unit in said chamber comprising coacting vertically spaced upper and lower walls arranged to define a transverse air inlet compartment in said chamber, a motor in said compartment, an air delivery throat in the upper wall, said motor extending partially upwardly through said throat to dispose the entire motor in said inlet air stream compartment and in the throat air diversion portion thereof, a blower fan above said upper wall and connected with said motor to be driven thereby, perforate clothes supporting means extending across said cabinet chamber confining said fan thereunder and forming a fan air discharge compartment together with said upper wall, and a heating coil in said fan air discharge compartment, said coil being disposed in radially spaced relation about said motor and in the air supply stream supplying said fan compartment through said throat, and said fan providing means to draw inlet air away from said motor location for dispersion

into said clothes chamber through said perforate clothes supporting means.

14. In a clothes dryer of the character set forth and defined in claim 13, wherein the motor is provided with a cooling fan to supplement said blower fan and to draw cool inlet air through the motor parts and to direct such air toward said blower fan.

15. In a clothes dryer of the character set forth and defined in claim 13, wherein said blower fan comprises a plurality of annularly arranged blades operating in a path disposed radially outwardly with respect to said motor and to said heating coil, and said throat includes an upstanding flange to flank portions of the inner peripheries of said blades to counteract radially inward flow of pressurized air toward said motor at said flange location.

16. In a clothes dryer of the character set forth and defined in claim 13, wherein said blower fan includes auxiliary fan blades arranged for rotation adjacent said motor and within the confines of said heating coil to force inlet air away from the motor location and radially outwardly directly through said coil.

17. In a clothes dryer, a clothes retaining cabinet having an open bottom and vent means at the upper end thereof, and a drying mechanism housed within the cabinet adjacent the open bottom thereof comprising a base plate carried by said cabinet and peripherally terminating in inward spaced relation with respect to said cabinet walls, an annular division wall spaced above said base plate and having an air throat therein, a motor mounted upon the base plate and extending through said air supply throat, a blower unit driven by said motor and having blades arranged for operation about said throat and above said division wall, a circular heating coil interposed in radially considered relation between said fan and said motor in the path of the inlet air of said throat, and said fan blades functioning to draw inlet air away from said motor and through said coil for discharge into said cabinet to dry said clothes.

18. A clothes dryer comprising a clothes receiving cabinet having an air inlet end and an air conducting section, clothes supporting means in said air conducting section of said cabinet, and apparatus adapted to impel tempered clothes drying air into said air conducting section of said cabinet, disposed at said air inlet end of the cabinet, said apparatus comprising spaced walls defining a chamber having communication with said air inlet end of the cabinet, one of said walls extending across the cabinet and having an air passage throat therein, a motor supported in the chamber between said walls and partially disposed within said air passage throat, a fan connected with said motor having blades located for operation encircling the air passage throat to discharge air into and to move air through said air conducting section of the cabinet and through and into the clothes therein, and a heating coil for said cabinet supported in the path of the flow of air and in radially outwardly spaced relation with respect to said motor, said fan blades providing means to move air through said throat and the chamber between the spaced walls to keep the air in constant circulation about the motor location.

19. In a clothes dryer, a cabinet for supporting the clothes, said cabinet having an inlet opening, and a drying mechanism carried by said cabinet at said inlet opening comprising a base plate supported within the cabinet and in spaced relation to the cabinet walls at said inlet opening, a baffle plate connected with the walls of the cabinet and having an air passage throat therein communicating with the cabinet and with the chamber formed between said plates, a motor supported between said plates in the chamber therebetween and partially disposed within the throat of said baffle plate, a blower unit driven by said motor including a fan having blades arranged for operation in a path about the throat of said baffle plate and outside of the chamber established between said plates, and a heating coil supported radially

outwardly of the motor and adjacent the location of the fan blades to occupy a position in the path of the air flow in said throat, said fan blades providing means to move air through said cabinet inlet opening, through the plate defined chamber and through the throat over and across said heating coil in a direction away from the motor for delivery into the cabinet to contact and to dry the clothes, while simultaneously drawing all inlet opening air over and away from the location of said motor.

20. A clothes dryer comprising a container defining a clothes drying compartment, cover means at the upper end of the container, cooperative blower and heating units at the bottom of said container to force tempered air upwardly through said container, said container being vertically loaded and unloaded through said cover means, and coating clothes orientation and segregating means for said container to vertically group clothes for independent drying action within predetermined vertically limited portions of said container comprising at least one perforate clothes support assembly carried in a given relation with respect to the container transversely thereof and overlying the blower unit to establish means to hold stacked clothes in transversely distributed relation in the container over the blower air discharge stream, and at least one other elevated support assembly connected with said container to occupy a position spaced upwardly in the container above said first assembly to limit upward floating and tumbling action of the clothes carried upon said lower support assembly so as to confine the drying action of said lower group of moving clothes to said fractional portion of said container defined by said two support assemblies, said second elevated support assembly having a pivotal connection with said container to permit said assembly to swing out of its transverse position to allow clothes loading into the lower portion of the container for drying action between said assemblies, and said second elevated support assembly coating with said cover means to define a second clothes drying vertical container portion operatively separated from said first operative clothes drying portion, such clothes groups being independently segregated, but served by the continuous drying action of the same blower unit.

21. A clothes dryer comprising an upright container providing a clothes confining and drying compartment, blower means connected with said container to deliver an upwardly directed stream of clothes drying air through said container, and vertically spaced mechanisms traversing said container to divide its vertical height into separate independent drying zones accommodating individually selected groups of clothes for air manipulation and drying in said common air stream, said spaced mechanisms comprising a stationary perforate support in the lower part of said container, a cover arrangement at the upper part of said container, and at least one intermediate transversely disposed perforate clothes support positioned horizontally across said container to divide the latter into upper and lower segregated operative clothes drying zones to accommodate one or more separate individual clothes groups, said intermediate support being swingably connected with said container through a vertically adjustable hinge mechanism on said container comprising a bracket having pivotal means connecting said bracket and the intermediate support at a single point of support on said container, and said intermediate perforate support having marginal extremities extending about said container spaced inwardly with respect to said container and in the stream of drying air to permit free air flow about said intermediate support and between the zones divided by said support.

22. A clothes dryer comprising an upright cabinet, air propelling mechanism to discharge air into the cabinet with a force to agitate and float articles of clothing, said mechanism comprising a blower disposed within one

end of said cabinet and providing an upwardly and outwardly flared discharge mouth to force air directly vertically along the remaining length of said cabinet, said flared upwardly open blower mouth having a marginally arranged baffle traversing the cabinet and connected therewith to seal off the cabinet clothes drying area from the blower space of said cabinet, said clothes drying area of said cabinet including individual vertically arranged clothes processing zones defined by a lower perforate clothes supporting structure overlying the blower mouth and its baffle to establish a minimum elevated limit for clothes in the path of the air flow discharged from said blower, a cover structure on said cabinet to establish a maximum clothes working limit, and an intermediate clothes supporting structure dividing said cabinet into upper and lower vertically aligned clothes manipulating and working zones, said intermediate support comprising a rack to limit the action of the mixed clothing and air action in the volumetric zone adjacent the blower discharge area of the cabinet and to support other clothing at a minimum elevated position for action by residual air flow through an upper volumetric zone in said cabinet having its upper limit defined by said cover structure of the cabinet.

25. A clothes dryer comprising a cabinet providing an upright clothes confining and drying compartment, an openwork duct structure disposed transversely of the cabinet to support the articles of clothing in evenly distributed fashion over the entire cross sectional area of the drying compartment, and air impelling means located beneath said openwork duct structure to discharge a pressure stream of buoyant air upwardly into said cabinet to agitate and to float the articles of clothing confined within said cabinet, said openwork duct structure comprising a cellular honeycomb multiple duct member dividing the entire cross sectional area of the single open cabinet into plural contiguous and elongated air conducting chambers overlying the air impelling means, said ducts of the honeycomb member extending vertically over a given portion of the upright length of the cabinet and providing distributed air inlet openings positioned adjacent the air impelling means and similarly distributed air outlet openings located at a higher level in the cabinet for the support of the articles of clothing thereacross and in the path of the channeled and guided air streams emerging out of said elongated multiple ducts of the honeycomb member.

24. In a clothes dryer of the character set forth and defined in claim 23 with the addition of auxiliary clothes suspending means within said cabinet comprising an upwardly directed wall assembly located above said honeycomb member providing raised edge portions in elevated positions above said honeycomb member to establish support means upon which to festoon or drape articles of clothing over and upon said honeycomb member to further control and enhance the air penetration of said clothes and to counteract bypass action and short circuiting of the air emanating from said honeycomb member.

25. In a clothes dryer, a clothes compartment, air supply means to force air through said compartment and over the entire cross sectional area of the compartment, and a cellular structure located in said compartment and interposed between said air supply means and the clothes carrying zone of said compartment, said cellular structure comprising elongated walls defining connected individual ducts all extending lengthwise in the compartment and occupying a position across the entire cross sectional area of said compartment to support clothes at a given minimum elevation within said compartment, said individual ducts in the cluster of said cellular structure providing means to divide the air discharged from said air supply means into fractional adjacent jets all guided toward multiple divisional areas of the total cross sectional area of the cabinet to maintain a predetermined distributed all over and uniform air pressure pattern to serve each

corresponding proportional part of the clothes load that is superimposed and supported by said respective ducts of said cellular structure.

26. In a clothes dryer of the character set forth and defined in claim 25 wherein said compartment is of uniform cross sectional area in length, with said cellular duct structure walls being arranged to lie in planes that are disposed parallel to the longitudinal median axis of said clothes compartment to insure parallel channelling of the air to the point of discharge of said cellular duct structure adjacent the clothes carried on said duct structure.

27. A clothes dryer comprising a vertical clothes confining cabinet having parallel peripheral walls in the length thereof, clothes supporting mechanism in said cabinet, and air propelling means to direct a stream of air through the entire cross sectional area of said cabinet and in a direction parallel to the walls of the cabinet to penetrate the clothing deposited within the cabinet, said supporting mechanism comprising a multiple arrangement of vertically positioned contiguously connected ducts each functioning to independently direct a portion of the air discharged from said propelling means as a guided jet directed vertically upwardly into the cabinet area for uniformly distributed clothes penetration, and at least one auxiliary clothes support comprising a rack mounted upon one wall of the cabinet including pivotal means to hold said attached end of the rack at an elevation intermediate the height of the cabinet to provide means for supporting additional clothing articles over and across said cabinet and spaced from said first supporting mechanism, said cabinet having latch means to secure the free end of the rack in operative position within the cabinet.

28. A clothes dryer comprising a vertical clothes confining cabinet having parallel peripheral walls in the

length thereof, clothes supporting mechanism in said cabinet, and air propelling means to direct a stream of air through the entire cross sectional area of said cabinet and in a direction parallel to the walls of the cabinet to penetrate the clothing deposited within the cabinet, said supporting mechanism comprising a multiple arrangement of vertically positioned contiguously connected ducts each functioning to independently direct a portion of the air discharged from said propelling means as a guided jet directed vertically upwardly into the cabinet area for uniformly distributed clothes penetration, and a plurality of auxiliary clothes carrying supports mounted upon said cabinet at different elevations in said cabinet, one of said supports comprising swingable means attached to one of the cabinet walls and movable between an operative position extending across said cabinet and a stored position adjacent said one wall and providing means to limit the motion of certain of the clothes deposited in said cabinet and in the direction of the air stream flow.
